H. C. LORD

SPREADING DEVICE

Filed Sept. 6, 1924

FIG. 3.

FIG. 4

FIG. 2.

INVENTOR
Hugh C. Lord

UNITED STATES PATENT OFFICE.

HUGH C. LORD, OF ERIE, PENNSYLVANIA.

SPREADING DEVICE.

Application filed September 6, 1924. Serial No. 736,317.

The present device is designed to increase the size of an opening either by springing or breaking the walls of the opening. The device is exemplified as adapted to open the eyes of a spring. These eyes ordinarily require great pressure to spread them. The present device affords a sufficient power advantage to accomplish this with little effort. Features of the invention will appear from the specification and claims.

The invention is illustrated in the accompanying drawings as follows:

Fig. 1 shows an elevation of the device arranged in a spring eye previous to the spreading or opening of the eye.

Fig. 2 a similar view with the device operated to open the eye.

Fig. 3 shows a section on the line 3—3 in Fig. 4.

Fig. 4 a section on the line 4—4 in Fig. 2. 1 marks a spring eye having the usual end 2. The spreading device comprises two rods 3. These rods are preferably cylindrical in cross section and are mounted in bearing openings 4 in a block 5. The bearing openings 4 are parallel and run into each other slightly so that the rods 3 are in rolling contact. The rods have their outer ends bent up forming handles 6 by means of which the rods may be rolled relatively to each other.

The front ends of the rods have their one surface cut away at 7. These are opposingly arranged having the outer edges 8. This cut-away portion gives to the rods a cross section having one cross dimension, that is, the diameter of the cylindrical portion of the rod, greater than the cross section at right angles to the cut-away surface. When the cut-away portions are swung opposite each other the edges 8 are rolled around so as to be slightly closer to each other and thus permit the entrance of the rods into the eye 1. When the rods are rolled to bring the cut-away portions into alinement—in other words bring the greater cross dimensions of the rods into alinement, the greater combined dimensions of the rods interposed between the walls of the eye spread the eye as shown in Fig. 2. It will be noted that the rods roll on each other so that there is no friction whatever and in effect a toggle lever is formed with comparatively short operating arms giving a tremendous power

advantage increasing as the greater dimensions are brought into alinement.

In order to maintain the rods in similar opposing relation throughout their movement I provide the following mechanism: A post 9 extends upwardly and centrally from the bearing block 5. A sliding block 10 is mounted on the post 9. Links 11 are connected to the sliding block 10 by screws 12 and to the arms or handles 6 by screws 13. This arrangement maintains the post in a direction perpendicular to a line connecting the axes of the rods and consequently maintains the rods in a directly opposing relation throughout their rolling action. In order to conveniently hold the rods in the bearing openings I form an extension 14 on the post 9 which extends through the block 5. This may be headed over at the bottom of the block and thus form a means of securing the post. The extension passes between the rods, the rods having a half round groove 15 extending partially around the rods through which the extension passes. Thus the rods are keyed in the block.

In order to limit the outward movement of the arms a stop washer 16 may be formed on the top of the post 9.

What I claim as new is:

1. In a spreading device, the combination of two parallel opposing spreading rods, each having one cross dimension greater than another; means for holding the rods in alinement; and means rolling the rods to bring greater cross dimensions of the rods toward and away from alinement.

2. In a spreading device, the combination of two parallel opposing spreading rods in rolling contact, each having one cross dimension greater than another; means for holding the rods in alinement; and means rolling the rods to bring greater cross dimensions of the rods toward and away from alinement.

3. In a spreading device, the combination of two parallel opposing spreading rods, each rod having a portion of its surface cylindrical and a portion of the surface varying from the cylindrical forming one cross dimension greater than another; means for holding the rods in alinement; and means for rolling the rods.

4. In a spreading device, the combination of two parallel opposing spreading rods,

- each rod having a portion of its surface cylindrical and a portion of the surface varying from the cylindrical forming one cross dimension greater than another, said rods being in rolling contact; means for holding the rods in alinement; and means for rolling the rods on the cylindrical surfaces.
5. In a spreading device, the combination of two parallel opposing spreading rods, each rod having a portion of its surface cylindrical and a portion of the surface varying from the cylindrical forming one cross dimension greater than another; bearings for the rods having axes coincident with the axes of the cylindrical portions of the rods; and means for rolling the rods.
6. In a spreading device, the combination of two parallel opposing spreading rods, each rod having a portion of its surface cylindrical and a portion of the surface varying from the cylindrical forming one cross dimension greater than another, said rods being in rolling contact; bearings for the rods having axes coincident with the axes of the cylindrical portions of the rods; and means for rolling the rods.
7. In a spreading device, the combination of two parallel opposing spreading rods, each rod having a portion of its surface cylindrical and a portion of the surface varying from the cylindrical forming one cross dimension greater than another; bearings for said rods, having axes coincident with the axes of the cylindrical portions of the rods, said bearings opening into each other permitting the contact of the portions of the rods in the bearings; and means for rolling the rods.
8. In a spreading device, the combination of two parallel opposing spreading rods, each having one cross dimension greater than another; means rolling the rods to bring greater cross dimensions of the rods toward and away from alinement; and means maintaining similar opposing relations between the rods.
9. In a spreading device, the combination of two parallel opposing spreading rods, each rod having a portion of its surface cylindrical and a portion of the surface varying from the cylindrical forming one cross dimension greater than another; bearings for the rods having axes coincident with the axes of the cylindrical portions of the rods; means for rolling the rods; and devices acting on the bearings to maintain similar opposing relations between the rods.
10. In a spreading device, the combination of two parallel opposing spreading rods, each having one cross dimension greater than another; handles extending from the rods; bearings in which the rods are rotatively mounted; a post extending from the bearings; a sliding block on the post; and links connecting the sliding block with the handles.

In testimony whereof I have hereunto set my hand.

HUGH C. LORD.
